UNITED STATES PATENT OFFICE.

WILLIAM B. JOHNSON, OF ELKHART, INDIANA, ASSIGNOR TO FOSTER-JOHNSON REAMER COMPANY, A CORPORATION OF INDIANA.

ADJUSTABLE REAMER.

1,375,460.

Specification of Letters Patent. Patented Apr. 19, 1921.

Application filed February 10, 1919. Serial No. 276,222.

To all whom it may concern:

Be it known that I, WILLIAM B. JOHNSON, a citizen of the United States, residing in the city of Elkhart, county of Elkhart, and State of Indiana, have invented certain new and useful Improvements in Adjustable Reamers, of which the following is a specification.

My invention relates to machine tools and particularly to adjustable reamers.

An object of my invention is the provision of simple and effective means for adjusting the reamer blades for wear and the various sizes of bores. Another object of the invention is the provision of improved yieldable means for holding and seating the blades at both ends thereof. A further object of the invention is the provision of improved means for eliminating vibration in the blade adjustment plunger. Other objects of my invention are mentioned and described hereinafter.

The preferred embodiment of my invention is illustrated in the accompanying drawing in which Figure 1 is an end view of the reamer; Fig. 2 is a longitudinal section through the reamer taken on the line 2-2 of Fig. 1; and Fig. 3 is a section through the holder taken on the same line as Fig. 2 and Fig. 4 is an end view of the holder.

Similar numerals of reference indicate like members and parts of members throughout the several views on the drawing.

On the drawing, the numeral 1 indicates the reamer body or holder which comprises the cylindrical enlarged blade carrier portion 2, the stem portion 3 and the reduced front end portion 4. The holder 1 is provided with the central bore 5 which is open at both ends and which may be of uniform diameter throughout, same being adapted to carry the blade actuation plunger, as hereinafter described. The blade carrier portion 2 of the holder is provided with a plurality of longitudinal and radially formed blade slots 6 which intersect the bore 5. The holder 1 is provided also with an abutment portion 7 at the rear end thereof which includes the arcuate nut slot or recess 8, said nut slot being adapted to be engaged by the shouldered portion of an adjustment nut hereinafter described.

Numerals 9 indicate a plurality of cutter or reamer blades mounted and radially

movable within the blade slots 6, each blade being beveled at opposite ends at 10 and 11 and having a pair of semicircular seats 12 and 13 on the inner periphery thereof which seats project slightly into the holder bore 5. The numeral 14 indicates a cylindrical blade actuating plunger slidably mounted in the holder bore 5 and provided with a pair of countersunk cam sections 15 and 16 which are engaged by the blade seats 12 and 13, said cam sections being formed by the convergence of the frusto conical portions 17 and 18. Intermediate the cams 15 and 16 the plunger 14 is provided with the cylindrical bearing section 19 adapted to fit the holder bore 5 closely but slidably, whereby elimination of all vibration in the plunger 14 is effected, especially between said cam sections when the reamer is performing heavy duty. The blades 9 are yieldably confined upon the cams 15 and 16 by a pair of bevel faced annular collars 20 and 21 which overlie the beveled blade ends 10 and 11, respectively. The end collar 20 is slidably mounted upon the holder portion 4 and is pressed into blade engagement by a plurality of springs 22 which are seated in recesses 23 formed in the spring seat collar, or washer, 24 also slidably sleeving the holder portion 4, said collar 24 being maintained in position by the end collar 25 which is screw threaded upon the holder portion 4 at 26.

The collar 25 is provided with the annular extension 27 which sleeves the collar 24 and the annular reduced portion 28 of the collar 20 for the purpose of excluding metal particles and abrasive matter. The use of the collar 24 is important because it does not rotate when the collar 25 is assembled upon the holder, whereby distortion and disarrangement of the springs 22 are effectually prevented.

The numeral 29 indicates an annular thrust collar in contact with the collar 21 and slidably mounted upon the holder stem 3 and suitably recessed at 30 to receive and seat the springs 31, the opposite ends of said springs being seated in the recesses 32 formed in a stop collar 33. Numeral 34 indicates a hollow cylindrical member detachably sleeving the holder stem 3 and which may be detachably secured thereto by a set screw 35, the forward end of which sleeve is extended at 36 to sleeve the collars 110

29 and 33 to exclude metal particles and abrasive matter. The collar 33 may be secured to the holder stem 3 by any suitable means, as a set screw—not shown—or the 5 engagement of the forward end of the sleeve 34 may be relied upon to perform that function. The rear end of the sleeve 34 may be formed with the annular enlarged bore or chamber 38 which normally encompasses 10 the holder abutment portion 7.

The numeral 39 indicates an annular adjustment nut mounted upon the screw threaded portion 40 of the plunger 14 which plunger extends beyond the end of 15 the holder stem 3 and the sleeve 34 for that purpose, said nut having an annular shouldered portion 41 which is arranged for rotation within the semicircular slot 8. In assembling the spindle or plunger 14 20 and the nut 39 the shoulder 41 of the latter is passed through the chamber 38 eccentrically of the stem bore 5 and into the slot 8, the plunger 14 being thereafter screwed into the threads of the nut 39 until 25 the desired position thereof is obtained.

Obviously, rotation of the adjustment nut 39 effects a longitudinal movement of the plunger 14, thereby causing the cams 15 and 16 to engage the blade seats 12 and 13, 30 whereby radial outward movement of the blades is effected, said nut 39 always remaining stationary, so far as longitudinal movement is concerned, on account of the engagement of the shoulder 41 with the slot 8.

35 For rotating the reamer, when in use, suitable handles—not shown—may be fastened to the sleeve 34, or the sleeve exterior may be formed for wrench engagement for that purpose.

40 I claim:

1. A metal cutting tool comprising, in combination, a body member or holder provided with a central bore; a plurality of radially movable blades mounted in said 45 holder; a longitudinally movable plunger mounted in said holder bore and adapted to radially actuate said blades when longitudinally moved; and means for longitudinally actuating said plunger, said means compris-

ing a revoluble adjustment nut sleeving said 50 plunger, a complementary spiral connection between said nut and said plunger, a slotted abutment member carried by said holder, and an annular shouldered member carried by said nut and revolvably arranged within 55 said abutment slot.

2. In a metal cutting tool of the class described, a holder; a plurality of adjustable cutter blades mounted radially in said holder; a spring pressed collar slidably 60 mounted upon said holder and adapted to inwardly actuate said blades; a spring seat collar movably mounted upon said holder; and a sleeve member detachably mounted upon said holder and adapted to form an 65 abutment for said spring seat collar.

3. In a metal cutting tool of the class described, a holder; a plurality of adjustable cutter blades mounted radially in said holder; a spring pressed collar slidably 70 mounted upon said holder and adapted to inwardly actuate said blades; and a second collar detachably mounted upon said holder and provided with an extension which sleeves said spring pressed collar. 75

4. A metal cutting tool comprising, in combination, a holder provided with a central bore; a plurality of radially movable blades mounted in said holder; a longitudinally movable plunger mounted in said 80 holder bore and adapted to radially actuate said blades when longitudinally moved; a revoluble adjustment nut; a complementary spiral connection between said nut and said plunger; a complementary shoulder and 85 slot connection between said nut and said holder, whereby, when said nut is rotated, said plunger is longitudinally actuated; and a chambered member carried by the holder adjacent said shoulder and slot connection, 90 the chamber whereof is adapted to enable the effectuation of the shoulder and slot connection between said adjustment nut and said holder.

In testimony whereof I have hereunto affixed my signature this 31st day of Jan., 1919.

WILLIAM B. JOHNSON.
